CLOTH GUIDING DEVICE

Charles G. Richardson, Springfield, Vt., assignor
to Parks & Woolson Machine Company, Spring-
field, Vt., a corporation of Vermont

Application September 14, 1933, Serial No. 689,384
Renewed September 23, 1938

8 Claims. (Cl. 271—2.6)

This invention relates to cloth finishing machines and is intended to provide a simple and efficient means for guiding the cloth as it travels into and through the machine so that the edge 5 of the cloth maintains a substantially constant line of travel as it approaches the cloth finishing devices such as selavage loop cutters, edge trimmers or otherwise instead of swerving in and out as heretofore when fed rapidly through a machine of this type.

Broadly speaking, this maintenance of the travel of the cloth edge in a substantially straight line is effected by means of a cloth engaging and guiding element or frame that is movable to and fro to counteract the swerving tendency of the cloth approaching the cloth finishing devices so that as the edge of the cloth passes such devices it will maintain a practically constant relation to said devices and thus avoid damage to the cloth.

In the accompanying drawings I have illustrated two different forms of construction embodying the principles of this invention in which

Fig. 1 is a plan view of a transversely movable cloth guiding frame combined with a feeler controlled mechanism which moves the frame in or out as the edge of the cloth swerves out or in.

Fig. 2 is a front elevation of the construction shown in Fig. 1.

Fig. 3 is a sectional view on plane 3—3 of Fig. 1 showing the apparatus as viewed from the outside of the edge of the cloth.

Fig. 4 is a detailed view showing an elevation from the inside of the feeler mechanism and the rotary ratchet shafts through which to and fro movement is imparted to the guide frame as required.

Fig. 5 is a plan view showing a modified form of construction in which the cloth guiding element or frame is pivoted to move to and fro about a vertical axis under the control of feeler controlled actuating mechanism.

Fig. 6 is a front elevation of the construction shown in Fig. 5.

Fig. 7 is a side elevation on the sectional plane line 7—7 of Fig. 5 illustrating the travel of the cloth through the guiding element by the feeler into the finishing machine.

Fig. 8 is a bottom plan view of the double toothed pawl showing the reversely inclined teeth for engaging the oppositely pitched ratchet threads to traverse the pawl in or out, respectively.

The device illustrated in the drawings is shown in the form of an attachment that can be mount-

ed at the front of a cloth finishing machine to control the guiding of the cloth as it passes rearwardly to be operated upon by the edge trimming, loop cutting or other finishing devices.

The cloth guiding member as shown in Figs. 5 1, 2 and 3 consists of a truck or carriage mounted to travel on tracks 2a transversely of the direction of the travel of the cloth. The carriage or truck comprises end frames 1 in which are mounted a forward cloth engaging and supporting bar 3, a rear supporting and engaging bar 4 at about the same level and an intermediate lower bar 5. The end frames are provided with flanged wheel trucks 2 adapted to travel in and out or transversely of the cloth on the tracks. 15 On the frame A of the machine is mounted a horizontal bracket or strut 7 carrying upright ends 6 which are provided with bearings for an upper rotary shaft 10 and an underneath or lower rotary shaft 11, said shafts being provided with helical threads intermediate their bearing ends and being operatively connected by intermeshing pinions 9 to rotate in opposite directions at uniform rates of speed. The rotation is effected by a pulley 12 secured to the projecting outer end of one of said shafts and the shafts are mounted in parallelism with and close to the adjacent side of the movable guide element.

Since the cloth has gone rapidly through the staggered tension and guide bars 3, 4 and 5 and is supported by said guide bars obviously the inward and outward movements of the carriage will tend to carry the cloth with it. This tendency is utilized by providing a feeler controlled mechanism, the feelers of which are arranged close to the normal edge line of the cloth so that any tendency of the cloth to swerve inward will result in an outward movement of the guide element which serves to counteract the inward swerving tendency and thus maintain the line 30 of travel of the edge of the cloth substantially constant.

I will now describe the mechanism by which this counteracting movement of the cloth guide is effected by means of the cloth itself.

Between the two oppositely rotating ratchet shafts 10 and 11 is mounted a pivotal dog 17 whose inner end overbalances the outer end so that when unrestrained by the feeler mechanism the inner end tends to drop about the horizontal pivot post 16a and allow the upper tooth 17a of the dog to engage the under side of the upper ratchet shaft. There is also a downwardly projecting lip or tooth 17b on the outer end of the ratchet dog that drops into engagement with 45 50 55

the lower ratchet shaft 11 when the outer end of the dog is depressed.

In Fig. 2 and in Fig. 3 the dog or pawl 17 is shown in neutral position with its ratchet 5 teeth out of engagement with both the upper and the lower ratchet shafts.

The position of the toothed dog 17 is determined or controlled by the position of the feelers 20, 21. These feelers are sector shaped and have 10 their upper arcuate edges serrated to engage and be dragged rearwardly with the cloth whenever the edge portion of the cloth travels above the plane of the feeler. The feelers are loosely mounted for limited independent movement 15 upon a horizontal shaft 23 whose axis is parallel with the axes of the ratchet shafts and is supported by upward extensions 13a of a sliding bracket 13, which is supported by a horizontal bar 12 mounted in the stationary or fixed end 20 bracket 6 that also supports the rotary ratchet shafts as best shown in Fig. 3. A clamping screw 14 serves to firmly hold the bracket 13, 13a in properly adjusted position to position the feelers 25 in proper relation to the edge line of the cloth. As shown in Fig. 3 the bracket 13a is provided with a laterally projecting stop pin 13b which limits the rearward movement of the feeler dogs 20, 21. Between the inner feeler 20 and the outer feeler 21 is a plate 22 which is secured to the 30 outer feeler 21 and which is provided with an inwardly offset extension 22a whose outer rearwardly turned end 22a is mounted on the feeler supporting shaft 23 and this extension arm 22a overhangs a pin 17c that projects from the forward face of the outer end of the pawl 17. This pawl actuating arm 22a when rocked downward (Fig. 3) will depress the outer end of the ratchet dog 17 to engage the lower ratchet shaft 11. It will be understood that the outer feeler 21 and 35 its attached plate 22 are provided with an inwardly projecting pin 21a passing through an arcuate slot 20a formed in the inner feeler 20.

The feeler devices are positioned so that the inner feeler 20 is beneath the extreme edge portion 40 of the traveling cloth by which it is engaged and moved back to the limit of its movement established by the stop pin 13b.

The inner feeler when moved to its rearward position by contact with the cloth acts through 45 its slot and pin connection to drag the outer feeler 21 to its middle position as shown in Fig. 3 so that the pawl actuating arm 22a through its engagement with the pin 17c keeps the pawl in neutral position. Should the cloth swerve inwardly out of engagement with the inner feeler 20 the feelers will be released and will tip forwardly under the influence of gravity. This forward tipping raises the arm 22a and allows the weighted inner end of the pawl 17 to drop there- 50 by causing engagement of the upper tooth 17a of the pawl with the upper ratchet 10. As a result of this engagement the carriage instantly moves the cloth back to engagement with the inner feeler 20 and the pawl is restored to neutral position.

Should the cloth tend to swerve outwardly into engagement with the outer feeler 21, such engagement drags the feeler 21 rearwardly to the limit of its rearward movement established by 55 the stop pin 13b thereby depressing the outer end of the pawl 17 by means of the actuating arm 22a and the pin 17c so that the lower tooth 17b will engage the lower ratchet 11. This instantly shifts the carriage inwardly causing the cloth 60 to lose contact with the outer feeler 21 and re-

main in contact only with the inner feeler at which position the pawl is in neutral. It will therefore be seen that just as soon as there is any tendency for the cloth to swerve inward or outward beyond the line of the feeler, there is 5 instantly set up a counteracting movement of the ratchet so that the travel of the edge of the cloth is maintained on a practically straight line, there being a sufficient space between the movable guide and the line where the cloth enters the 10 finishing machine so that the counteracting tendency of the guide fully offsets the initial swerving tendency of the cloth. It is therefore possible to pass the cloth into the finishing machine at a constant or fixed line defining its edge. 15

The form shown in Figs. 5-7 illustrates the action of a feeler controlled mechanism on a pivotally mounted oscillatory cloth guide. In this form the guide frame 30 has upright end members 30a which carry three staggered guide 20 bars 31, 22 and 33. At its middle portion the frame 30 is supported on a swivel post 34 mounted in bearings provided in a fixed support 35. On the pivot post 34 is secured an outwardly projecting arm 37 whose outer end is connected 25 by a link 38 with one arm of a bell-crank lever 38a, whose other arm is slotted to engage a pin or roller 39 carried by a slide bar 40 which has sliding support in the end brackets 36a of a fixed frame 36. 30

A bracket 41 projects upward from the slide bar 40 and on this bracket is pivoted, about a horizontal axis parallel with the direction of travel of the cloth, a feeler dog 42 having at its middle an upstanding feeler finger 43 adapted 35 to form a flat face contact with the traveling edge of the cloth. Beneath this dog 42 is a rotary ratchet shaft 37 having reverse helical threads 37a intersecting each other, one of which, when engaged by one tooth of the dog, pushes 40 the dog outward, the other pushing the dog inward when engaged by the opposite tooth of the dog. The inner end of the dog is weighted or overbalanced in order to cause the finger 43 to contact lightly with the edge of the cloth. 45

When the cloth edge is traveling along its normal line, the contact of the cloth against the finger keeps the pawl in neutral position. If the cloth moves slightly inward, the feeler follows it owing to the overbalancing gravity of the inner 50 end of the pawl and the inner tooth engages the ratchet thread that pushes against its abrupt face to push the pawl outwardly, until the pawl is restored to neutral. On the other hand any tendency to outward swerving of the cloth edge 55 results in tipping the outer tooth of the pawl into engagement with the reverse thread of the ratchet which pushes the pawl inwardly to neutral.

Since the pawl is pivotally attached to the 60 transverse slide bar, it will be apparent that the to and fro thrust of the pawl or dog 42 is transmitted to the slide bar 40 and thence through the link-connected arms 38a and 37 to oscillate the frame as required to guide the cloth inward 65 or outward in counteraction of the outward and inward movements of the cloth. Hence in both cases just as soon as the cloth starts to swerve in one direction such movement is corrected by means that are directly responsive to the movement of the cloth so that, from the automatic feeler controlled guide, the cloth edge travels to the finishing devices along a practically straight line. 70

While for the purpose of illustration I have 75

shown rotary ratchet members associated with a feeler controlled pawl for shifting the guiding element to swerve-counteracting position, it will be understood that the invention is not limited 5 to any particular kind of guide actuating means for counteracting the swerving movements of the cloth through the medium of the initial lateral movements of the cloth edge.

What I claim is:

1. A feeler mechanism for guiding a web of cloth against swerving and controlled by in and out movements of the cloth edge embracing a pawl, a pair of side by side pivotal feeler dogs capable of independent movements supported to 15 lie on opposite sides of the desired line of travel of the edge of the cloth, one of said dogs being provided with a pawl engaging finger for retaining said pawl in neutral position when said dog is not engaged by the cloth, and acting to release the pawl for movement from neutral when 20 neither dog is engaged by the cloth, a pawl and ratchet mechanism, the pawl of which is controlled by the feelers as aforesaid, and cloth guiding means shiftable by said ratchet and pawl 25 to exercise guiding control over the cloth.

2. In a device for guiding a travelling web of cloth against lateral swerving from its normal path, the combination of cloth supporting and guiding means movable to and fro, reversely acting 30 continuously rotating threaded actuating means for moving the guiding means in opposite directions, a pawl associated with said cloth supporting and guiding means, means for pivotally supporting the pawl for movement in one direction into operative engagement with one of said actuating means and in the opposite direction into operative engagement with the other of said operating means, means associated with the pawl for constantly urging the same into operative engagement with one of said actuating means and pivotal means for engaging and being actuated by engagement with the margin of the cloth and having direct engagement with said pawl for movement of said pawl into operative 40 engagement with the other of said actuating means.

3. In a device for guiding a travelling web of cloth against lateral swerving from its normal path, the combination of cloth supporting and guiding means movable to and fro, reversely acting 45 continuously rotating threaded actuating means for moving the guiding means in opposite directions, a pawl associated with said cloth supporting and guiding means, means for pivotally supporting the pawl for movement in one direction into operative engagement with one of said actuating means and in the opposite direction into operative engagement with the other of said operating means, means associated with the 50 pawl for constantly urging the same into operative engagement with one of said actuating means and means associated with said pawl and engageable by the margin of the cloth for movement of the pawl into operative engagement with the other of said actuating means.

4. In a device for guiding a travelling web of cloth against lateral swerving from its normal path, the combination of cloth supporting and guiding means movable to and fro, reversely acting 55 continuously rotating threaded actuating means for moving the guiding means in opposite directions, means associated with said cloth supporting and guiding means for alternate engagement with either of said actuating means and including means for engaging and actuation by

engagement with the margin of the cloth for movement of the associated means towards one of said actuating means, said associated means including means for constantly urging the associated means towards the other of said actuating 5 means.

5. In a device for guiding a travelling web of cloth against lateral swerving from its normal path, the combination of cloth supporting and guiding means movable to and fro, reversely acting 10 continuously rotating threaded actuating means for moving the guiding means in opposite directions, a pawl associated with said cloth supporting and guiding means, means for pivotally supporting the pawl for movement in one direction into operative engagement with one of said actuating means and in the opposite direction into operative engagement with the other of said operating means, and means responsive to initial opposite swerving movements of the cloth for 15 effecting movements of the pawl for selective engagement with the respective reversely acting guide actuating means to move the guiding means in a direction appropriate to oppose the initial swerving movement of the cloth. 20

6. In a device for guiding a travelling web of cloth against lateral swerving from its normal path, the combination with cloth supporting and guiding means movable to and fro, of means responsive to the in and out movement of the cloth 25 edge and having an operative engagement with the guiding means for controlling the movement of the guiding means to counteract the swerving movement of the cloth, said responsive means comprising reversely acting continuously 30 rotating threaded means, means adapted to be brought into operative engagement with one of said reversely acting threaded means for movement of the guiding means in one direction and with the other of said reversely acting threaded 35 means for movement in the opposite direction, and means for engaging and actuation by engagement with the margin of the cloth for controlling the movements of said means for engaging the reversely acting threaded means. 40

7. In a device for guiding a travelling web of cloth against lateral swerving from its normal path, the combination of cloth supporting and guiding means movable to and fro, a continuously 45 rotating shaft having right and left hand threads cut thereon, a pivoted pawl operatively connected to the cloth supporting and guiding means for movement thereof, said pawl having teeth thereon, one of which is adapted to be brought into operative engagement with the left hand threads 50 and the other tooth into operative engagement with the right hand threads, means for constantly urging the pawl in one direction to bring one of said teeth into operative engagement with its threads and means associated with said pawl for engaging and actuation by engagement with the margin of the cloth for moving said pawl in the opposite direction to bring the first tooth out of engagement with its threads and the other tooth 55 into engagement with its threads. 60

8. In a cloth finishing machine having a cloth guiding member which is mounted for to and fro movements to counteract swerving movements of the cloth, the combination of a dog associated 70 with the guiding member, said dog being pivoted between its ends for movement about an axis parallel to the direction of travel of the cloth, a rotary shaft having right and left hand threads cut thereon, said pawl having a tooth at one end

adapted to engage the left hand threads for movement of the pawl and thereby the guiding means in one direction, said pawl having a tooth at its other end adapted to engage the right hand threads for movement of the pawl and thereby the guiding means in the opposite direction, means associated with the pawl for moving

the same in one of said directions and an upright finger associated with said pawl and engageable by the extreme edge of the cloth passing by for movement of the pawl in the opposite direction.

CHARLES G. RICHARDSON.
